UNITED STATES PATENT OFFICE.

IRA R. SELTZER, OF WATERBURY, CONNECTICUT, ASSIGNOR TO THE GORDON ELECTRIC MFG. CO., OF WATERVILLE, CONNECTICUT.

ELECTRIC INSTALLATION FIXTURE.

Application filed June 12, 1919. Serial No. 303,565.

To all whom it may concern:

Be it known that I, IRA R. SELTZER, a citizen of the United States, residing at Waterbury, in the county of New Haven and State of Connecticut, have invented a new and useful Improvement in Electric Installation Fixtures; and I do hereby declare the following, when taken in connection with the accompanying drawings and the characters of reference marked thereon, to be a full, clear, and exact description of the same, and which said drawings constitute part of this application, and represent, in—

Fig. 1 a front view of a screw-plug flush-receptacle embodying my invention.

Fig. 2 an end view of the insulating body thereof, as it appears when stripped.

Fig. 3 a back view of the complete fixture as shown in Fig. 1.

Fig. 4 a sectional view of the insulating body on the line 4—4 of Fig. 3, the body being shown stripped, as also shown in Fig. 3.

Fig. 5 a view of the fixture in central longitudinal section on the line 5—5 of Fig. 1.

Fig. 6 a broken sectional view on the line 6—6 of Fig. 1.

Fig. 7 a broken sectional view on the line 7—7 of Fig. 1.

Fig. 8 a detached plan view of the screw-shell with the arms thereof bent at right angles to its axis.

Fig. 9 a view of the shell in side elevation prior to the bending of the arms.

Fig. 10 a broken sectional view on the line 10—10 of Fig. 1.

My invention relates to an improvement in electric installation fixtures such as receptacles, sockets, cut-outs and the like, the object being to reduce the cost and number of parts of articles of this character, as well as to improve their efficiency and appearance.

With these ends in view, my invention consists in certain details of construction and combinations of parts as will be herein-after described and pointed out in the claim.

For the purpose of illustrating my invention, I have shown it as applied to what is known as a screw-plug flush-receptacle, but it is equally applicable to other forms of electric installation fixtures, such as sockets, cut-outs and the like. As herein shown, I employ a metal screw-shell 11 having a pair of integral complementary assembling arms

12, 12, formed upon its lower edge at points opposite each other. The shell is also formed with an integral current-carrying arm 13 which is longer than the arms 12, 12, aforesaid, and located midway between the same and constitutes one of the salient features of my present invention. The said shell is located in a circular chamber 14 formed in and entering the front face of the molded insulating body 15 of the fixture, the said body being made of porcelain or other suitable material. In the bottom edge of the circular chamber 14 I form two oppositely located complementary passages 16, 16, for the respective assembling-arms 12, 12, and with a passage 17 for the current-carrying arm 13 which is bent outward at a right angle into a recess 18 formed in the back of the body 15 as shown in Fig. 7 and extending laterally outward with respect to the axis of the chamber 14. The outer end of the said arm 13 is formed with a hole for a current-carrying screw 19 extending forward through a screw hole 20 in the body 15 and screwed into a terminal 21 located in a recess 22 in one corner of the front of the body 15, the said terminal which is thus held in place, being furnished with a binding screw 23 for the reception of a current-carrying wire, not shown. Under the construction just described, the current-carrying arm 13 is made to take the place of the several connecting segments ordinarily employed for carrying the current from the screw-shell to the terminal in question.

The passages 16, 16, aforesaid lead into recesses 24 in the back of the body 15 as shown in Figs. 3 and 6, the ends of the assembling-arms 12, 12, being bent outward in these passages. For the purpose of increasing the grip of the arms 12, 12, the floors of the recesses 24, 24, have their outer ends inwardly inclined as at 26 to permit the outer ends of the arms to be bent at more than a right angle as shown in Fig. 6, whereby the grip of the said arms upon the body 15 is made stronger.

To facilitate the assembling operation, the entrance to the passages 16, 16, and 17 are flanked by assembling or guiding lugs 27 as shown in Figs. 6 and 7, the outer faces of these lugs merging into assembling or guiding inclines 27^a which tend to bend the arms 12, 12, and 13 outward as the shell is crowded home in the chamber 14. This

construction facilitates the assembling operation, since otherwise the ends of the respective arms must be accurately positioned with respect to the several passages before the shell can be shoved home.

The "shell current", as it is commonly called, is carried as already described, by the current-carrying arm 13, the screw 19, and the terminal 23. The "center current", 10 so called, is provided for in the usual manner by a center contact strip 28 extending radially into the bottom of the chamber 14 and resting upon a slight elevation 29 therein. The outer end of the said strip passes 15 outward through a lateral opening 30 in the bottom of the chamber 14 into a recess 31 in the back of the body 15. A current-carrying screw 32 passing through the outer end of the strip 28 and through a hole 33 20 in the body 15, carries the "center current" to a terminal 34 in a recess 35 in the front of the body 15, this being a common construction. The body 15 is furnished at its ends with fastening brackets 36 secured in 25 place by screws 37.

While I have shown my invention as applied to a screw-plug flush-receptacle, it is apparent that sockets, cut-outs or the like may in the same manner have their screw-shells provided with integral current-carrying arms corresponding to the arm 13 and used for the same purpose. It is also apparent that kindred electric installation fixtures may have the floors of the recesses 30 formed in their insulating bodies for the reception of the assembling-arms of their 35

shells inclined to permit the arms to be bent at more than a right angle for strengthening their grip, and that the passages into such recesses may be flanked with assembling-lugs leading to inclines, the construction and the functions of these features remaining the same irrespective of the particular use of the fixture.

I claim:-

In an electric installation fixture, the combination with an insulating body having a screw-shell-receiving chamber entering its front face, and passages leading from the bottom of the said chamber into complementary recesses located in the rear face of the said body, and assembling lugs flanking the said passages and having walls inclined with respect to the said recesses; of a screw-shell located in the said chamber 50 and having at its inner end assembling arms and a current-carrying arm respectively entered into the said recesses through the said passages and deflected outwardly by the said lugs; a current-carrying screw located in a 55 hole in the said body; and a terminal located in the front face of the said body and connecting the said terminal with the current-carrying arm of the shell.

In testimony whereof, I have signed this 60 specification in the presence of two subscribing witnesses.

IRA R. SELTZER.
